UNITED STATES PATENT OFFICE.

GEORGE WESTINGHOUSE, JR., OF PITTSBURG, PENNSYLVANIA.

IMPROVEMENT IN ROTARY VALVES FOR STEAM-ENGINES.

Specification forming part of Letters Patent No. 138,828, dated May 13, 1873; application filed February 15, 1873.

To all whom it may concern:

Be it known that I, GEORGE WESTINGHOUSE, Jr., of Pittsburg, in the county of Allegheny and State of Pennsylvania, have invented a new and useful Improvement in Rotary Valves for Steam-Engines; and I do hereby declare the following to be a full, clear, and exact description thereof.

My present invention relates to improvements in the class of steam-engines described in patents granted to me August 30, 1870, No. 106,899; June 6, 1871, No. 115,668; and October 8, 1872, No. 131,985; and more particularly to the devices by means of which the auxiliary or reversing engine therein shown is operated.

To enable others skilled in the art to make and use my invention, I will proceed to describe its construction and mode of operation, referring for that purpose to the accompanying drawing making a part of this specification, in which—

Figure 1 is a vertical sectional view through the axial line of the reversing-cylinder, through the valve-chamber at right angles to the axial line of the valve, and down through the base block, which rests on or constitutes the upper head of the main cylinder. Fig. 2 is a sectional view through $\alpha\alpha$ of Fig. 1. Fig. 3 is a detached view of the valve devices of Figs. 1 and 2, but drawn out on the valve-stem so as to give a separate view of each; and Figs. 4 and 5 are detached views of parts, hereinafter described.

Like letters of reference indicate like parts in each.

The auxiliary or reversing cylinder B, the valve-box B^1 , and base block B^2 are substantially of the same construction, relative arrangement, and operation as in the patents above named, as also are the piston D with its stem and eye D' , and the valve-stem f, knob f^2 , and shoulder f^1 . The valve n is also made as in patent No. 131,985, except that the steam-port s is made in its periphery, two exhaust-recesses, v v, on opposite sides, with suitable exhaust-ports, take the place of the exhaust-groove there shown, and an oil-groove, s' , is made along lengthwise of the lower periphery for convenience in keeping the valve well oiled. The valve-seat m is of the same construction and operation as in the patent last named.

The other steam-ports are also the same, except that an exhaust-port, v' , leads from one recess v to the opposite exhaust-port w, for reasons which are apparent on examination of the drawing.

In the present improvement the valve-stem g, on which is arranged the valve n and the rocking block g' , has a collar, e, near one end, in such position that the end of the valve n will bear against it; then the steam that leaks past the valve and that end of the stem will so far counterbalance the steam pressure on the other end of the valve n that the latter while working closely on its seat will not wedge in so tightly as to occasion serious loss by excessive friction. The opposite end of the stem g passes through a stuffing-nut in the valve-box B^1 so as to be capable of a free end play, so far as may be necessary to relieve the valve of excessive friction. The rocking block g' has a sleeve, i, which passes through the valve n, and dowel-pins $i^1 i^2$, by which it is connected with the valve. On one of these pins, i^1 , I slip the slotted eye h, which is made in the upper end of the stem f. This eye is long enough to allow the pin i^1 to play back and forth so far as may be necessary in its rotary motion. By means of this stem and crank motion the valve is rotated back and forth so as to bring the steam-port s alternately to the ports c c', which ports communicate by the ports o o' with the opposite ends of the cylinder B; also, by the same motion the recesses v v are alternately brought into communication with the exhaust-ports u u', and z z', and v' v' so as to carry off the exhaust steam to a common exhaust-port, w. Steam is admitted into the chamber b by any suitable port, a.

I have found in practice that where the steam is allowed to press on the upper end of the enlarged part f^1 of the stem f such pressure was sometimes sufficient to force the stem down before the main piston in its downward stroke strikes the knob f^2 . To remedy this defect I make the stem f above the shoulder f^1 , as at r^1 , of less size—say, about the size required in the main part f^1 of the stem—and surround this reduced part r^1 with a bush, r, which may conveniently be made in two parts, and which is supported against the downward pressure of the stem by resting on a shoulder, r^2 , of the

base B². In this way I reduce the area of stem subject to effective downward pressure to such extent that the valve *n* is not liable to be reversed thereby.

What I claim as my invention, and desire to secure by Letters Patent, is—

1. The conical valve *n* subject to steam pressure at its larger end, in combination with the stem *g*, on which it rotates, and the collar *e* on said stem with a bearing against the smaller end of the valve, the opposite end of the stem *g* passing through a stuffing-nut so as to have a free end play, substantially as set forth.

2. The stem *f* having a shoulder, *f'*, and a reduced part, *r'*, above, in combination with a

bush, *r*, suitably seated or held in a fixed position, substantially as and for the purposes set forth.

3. The stem *f* connected by a slot-shaped eye at its upper end to a pin, *i'*, in combination with the rotary valve *n*, substantially as set forth.

In testimony whereof I, the said **GEORGE WESTINGHOUSE, Jr.**, have hereunto set my hand.

GEORGE WESTINGHOUSE, JR.
